VENTED FLUID CONTROLLING VALVE

Alberto Louis Maggenti, San Francisco, Calif.

Application November 2, 1934, Serial No. 751,132

12 Claims. (Cl. 225—5)

My present invention relates to a fluid controlling valve, and more particularly to an improved valve for withdrawing fluids from a sealed container, such as a barrel or the like, wherein it is necessary to provide an air vent to facilitate a withdrawal of the fluid therefrom.

An object of my invention is to provide a new and novel form of valve for withdrawing a fluid from a sealed container having means for venting the container when fluid is being withdrawn from the container.

Another object of my invention is to provide a new and novel form of vented valve having means wherein the vent may be optionally rendered operable and/or inoperable when the valve is opened.

Other objects and advantages of my invention will be in part evident to those skilled in the art and in part pointed out in the following description taken together with the accompanying drawing wherein there is shown, by way of illustration and not of limitation, a preferred embodiment thereof.

In the drawing, wherein like numerals refer to like parts throughout the several views;

Figure 1 is a vertical sectional view of valve constructed in accordance with a preferred embodiment of my invention.

Figures 2 and 3 are fragmentary sectional views taken from Figure 1, showing two positions of the parts when the valve is open,

Figure 4 is a view similar to Figure 1, showing a modified form of my invention,

Figures 5 and 6 are fragmentary sectional views taken from Figure 4, showing the relation of parts thereof when the valve is in its open position and the vent respectively opened and closed, and

Figure 7 is a vertical sectional view of a further modified form of my invention showing the parts of the valve in their valve closing positions.

As a preferred embodiment of my invention, I have shown in Figure 1 of the drawing a valve body member 10 having a screw threaded extension 11 that is adapted to be turned into the outlet of a barrel or the threaded outlet of a similar container. The valve body 10 also has a discharge outlet spout 12 over the inner end of which a valve member 13 is disposed. The valve member 13 is biased into sealing engagement with the inner end of the discharge outlet 12, by means of a spring 14, and connected to the valve member 13 there is a valve operating stem 15. The valve operating stem 15 extends through the spring 14 and out of the valve body 10 at a point

opposite the discharge outlet 12. At its upper end the valve operating stem 15 is provided with an operating lever 16 that is adapted to raise the stem 15 by compressing the spring 14 and thus opening the discharge outlet when pressure is applied thereto.

Extending through the wall of the valve body 10 there is a vent forming passageway 17 which terminates at one end adjacent the inlet to the valve and at its other end adjacent the valve member operating stem 15. Cooperating with the vent forming passageway 17 there is a vent aperture 18, which is formed in the valve operating stem 15, where it will align with the vent forming passageway 17 when the valve member 15 is raised to its valve open position. The vent aperture 18 is shown as extending diagonally and diametrically through the valve operating stem 15, so that when the valve operating stem 15 is in the position as shown in Figure 2 of the drawing, a vent passageway will be established from the atmosphere to the inlet end of the valve body 10.

At this point it should be stated that the operating valve lever 16 has a heel-like portion 19 that is adapted to be thrown over center to hold the operating lever 16 in its depressed position when the operator has released same. The heel 19 upon the operating lever 16 engages an annular boss 20 upon the valve body 10 and, as a result, it is possible to rotate the operating lever 16 and the valve operating stem 15 into the position illustrated in Figure 3 of the drawing, without necessitating or permitting a closing of the discharge outlet 12 of the valve. In this manner it is possible to optionally open and/or close the vent passageway formed, as above described, without closing the discharge outlet 12.

In Figure 4 of the drawing, the valve body 10 is similar to that illustrated in Figure 1, except that it is provided with a screw threaded portion 21 through which a threaded valve operating stem 22 is adapted to extend. The threaded valve operating stem 22 has an operating handle 23 and at its lower end it carries a valve member 24 that is adapted to close the discharge outlet 12 when the threaded valve operating stem 22 is turned downwardly into the valve body 10. In this embodiment of my invention, like the one previously referred to, the body member 10 has a vent forming passageway 17 that communicates with the threaded opening through which the valve operating stem 22 projects.

In order to provide for an opening of the vent forming passageway 17 to the atmosphere, when

the valve member 24 is in its discharge outlet opening position, the threaded valve operating stem 22 is provided with a cutaway portion 25 that is adapted to align with the vent forming 5 passageway 17 and thus establish a communication with the atmosphere externally of the valve body 10. This cutaway portion 25 is provided by slotting the threaded valve operating stem 22 for a short distance at a point adjacent 10 the end of the vent forming passageway 17. Such a slotting will destroy only a very small portion of the screw threads at this point and, as a result, it will be possible, after the valve member 24 has been moved into its open position, 15 to optionally open and/or close the air vent provided by the vent forming passageway 17 and the cutaway portion 25 upon the threaded valve operating stem 22. The position of the screw threaded operating stem 22, when the valve and 20 the vent are opened, is clearly illustrated in Figure 5 of the drawing, and the position of the threaded valve operating stem 22, with the valve open and the vent closed, is clearly shown in Figure 6 of the drawing.

25 In Figure 7 of the drawing, I have shown an embodiment of my invention, having a valve body 26 that is provided with a threaded inlet extension for attachment to a barrel or like container. In addition to this threaded inlet extension, the 30 body member 26 also has a discharging outlet spout 27 at its outer end. Located within the valve body 26 there is an annular valve seat 28 against which a valve member 29 is adapted to engage to close the valve. The valve member 29 is 35 mounted upon a tubular valve stem 30 and it is biased against the annular valve seat 28 by a spring 31. This tubular valve stem 30 extends through a thickened portion 32 at the outer end of the valve body 26. At this point the valve body 26 is provided with a bushing 33, in which 40 the tubular valve stem 30 will snugly fit and permit it to be both rotated and moved axially therein. Extending radially through the thickened portion 32 of the valve body 26 and the 45 bushing 33 there is a vent forming passageway 34 that is adapted to cooperate, as will hereinafter appear, with a vent aperture 35 formed at a properly located point through the tubular valve stem 30. Mounted upon and closing the outer 50 end of the tubular valve stem 30 there is an operating push button 36 by means of which the tubular valve stem 30 may be moved axially against the action of the valve member biasing 55 spring 31.

55 With this last above described embodiment of my invention, it will be seen that by pressing inwardly upon the operating push button 36, it will be possible to move the valve member 29 into its valve opening position and at the same time open 60 the vent forming passageway 34 to the interior of the tubular valve stem 30 and permit the entrance of air to the interior of the container from which fluid is being withdrawn. It will also be noted, since the vent aperture 35 comprises only 65 a small opening in one side of the tubular valve stem 30, that by a slight rotation of the operating push button 36 it will be possible to move the valve member 29 into its valve open position without establishing a venting communication 70 with the atmosphere through the tubular valve stem 30.

From the above it will be seen that I have provided a novel vented valve, which, in addition to controlling the discharge of fluid from the container, will also control the admission of air to

the container as the fluid is withdrawn therefrom. An advantage of my improved valve is that the auxiliary or air vent forming passageway through the valve may be optionally opened and/or closed, depending upon whether or not the fluid will flow 5 freely from the container. Another advantage of a valve constructed in accordance with my invention is that the air vent provided thereby must always be closed when the main fluid controlling valve is closed. This insures that only 10 sufficient air to facilitate a free flow of the fluid from the container will be admitted thereto and also provides against contamination of the fluid when the valve is closed.

While I have, for the sake of clearness and in 15 order to disclose my invention so that the same can be readily understood, described and illustrated specific devices and arrangements, I desire to have it understood that this invention is not limited to the specific means disclosed, but may 20 be embodied in other ways that will suggest themselves to persons skilled in the art. It is believed that this invention is new and it is desired to claim it so that all such changes as come within the scope of the appended claims are to be con- 25 sidered as part of this invention.

Having thus described my invention, what I claim and desire to secure by Letters Patent is—

1. In a vented valve for withdrawing fluids from a sealed container, the combination of a 30 valve body having means for attachment to the outlet of a sealed container, said valve body also having a main fluid passageway and an auxiliary air passageway adapted to communicate with the interior of the sealed container, a valve means 35 having an axial movement for opening said main fluid passageway and a rotary movement by which said auxiliary air passageway may be subsequently opened, whereby air will be admitted to the interior of said container as the fluid flows 40 therefrom through said main fluid passageway of the valve, and means whereby said auxiliary air passageway may be optionally opened and/or closed without closing the main fluid passageway 45 of the valve.

2. In a vented valve for withdrawing fluids from a sealed container, the combination of a 50 valve body having means for attachment to the outlet of a sealed container, said valve body also having a main fluid passageway and an auxiliary air passageway adapted to communicate with the interior of the sealed container, a valve means having an axial movement for controlling said main fluid passageway and a rotary movement for controlling said auxiliary air passageway, 55 whereby air will be admitted to the interior of said container as the fluid flows therefrom through the main fluid passageway of the valve body, and means for operating said valve member whereby said auxiliary air passageway may 60 be optionally opened and/or closed while the main fluid passageway of the valve is open.

3. In a fluid controlling valve, the combination of a valve body having a discharge outlet, a valve member operating within said valve body to close 65 said discharge outlet, and a valve member operating stem for imparting axial movement to said valve member to open and close said discharge outlet, said valve body also having a vent passageway extending from its fluid inlet end to a 70 point adjacent said valve member operating stem, and said valve member operating stem having a portion thereof adapted to cooperate with said vent passageway and by rotation thereof connect and/or disconnect said passageway with the 75

- atmosphere when the discharge outlet of the valve body is opened.
4. In a fluid controlling valve, the combination of a valve body having a discharge outlet and a portion adapted to be connected to a fluid supply, said valve body also having a vent passageway extending from its fluid inlet end to a point where a valve operating stem passes through the valve body, an axially movable valve member operating within said valve body to close said discharge outlet, and a rotatable valve operating stem passing through said valve body and connected to said valve member for controlling the position thereof with respect to said discharge outlet, said valve operating stem having an oblique aperture therethrough adapted upon rotation of said operating stem to be brought into and out of register with said vent passageway when said valve member is moved into its open position by said valve operating stem, whereby said vent passageway may be opened and/or closed to the atmosphere when the discharge outlet of the valve body is opened.
5. In a fluid controlling valve, the combination of a valve body having a discharge outlet, a valve member movable axially within said valve body to open and close said discharge outlet, and a rotatable valve operating stem for controlling the axial position of said valve member with respect to said discharge outlet, said valve body also having a vent passageway extending through the valve body to a point adjacent said valve operating stem, said valve operating stem having an opening therein adapted to be brought into and out of register with said vent passageway by rotation thereof to establish an air vent through the valve body when said valve member is in its open position with respect to the discharge outlet of said valve body.
6. In a fluid controlling valve for a sealed container, the combination of a valve body having a discharge outlet and a fluid intake end adapted to be connected to a sealed container, a valve member operating axially within said valve body to close said discharge outlet, and a rotatable valve member operating stem for controlling the position of said valve member with respect to said discharge outlet, said valve body also having a vent passageway extending through the valve body from its fluid intake end to a point adjacent said valve member operating stem, said valve member operating stem having an aperture therethrough adapted upon rotation of said stem to be aligned and disaligned with said vent passageway when said valve member is moved into its open position, whereby said vent passageway may be optionally opened and closed to the atmosphere when the discharge outlet of said valve body is opened.
7. In a vented fluid controlling valve for a sealed container, the combination of a valve body having an internal chamber adapted to connect with the interior of a sealed container and a vent passageway adapted to communicate with the interior of said container, a discharge outlet leading from the internal chamber of said valve body, a valve member operating to close said discharge outlet, spring means for biasing said valve member into a discharge outlet closing position, an operating stem connected to said valve member and extending through a wall of said valve body adjacent said vent passageway having an aperture therethrough adapted to register with said vent passageway, and means upon said operating stem for moving said valve member into a valve open position with respect to said discharge outlet and the aperture of said operating stem into register with said vent passageway, whereby said vent passageway will be opened to the atmosphere when the discharge outlet of the valve is opened.
8. In a vented fluid controlling valve, the combination of a valve body having an interior chamber adapted to communicate with a source of fluid supply, a discharge outlet upon one side of said valve body communicating with said chamber, a valve member within said chamber operating with said discharge outlet to open and close the same, said valve body also having a vent forming passageway extending along one side of said chamber and terminating opposite said discharge outlet, and a rotatable valve operating stem connected to said valve member extending through said valve body opposite said discharge outlet and having a portion adapted upon rotation of said stem to cooperate with said vent forming passageway to connect and disconnect it with the atmosphere when said valve member is in its open position with respect to the discharge outlet of the valve body.
9. In a vented fluid controlling valve, the combination of a valve body having an interior chamber adapted to communicate with a source of fluid supply, a discharge outlet upon one side of said valve body communicating with said chamber, a valve member within said chamber cooperating with said discharge outlet and operating to open and close the same, said valve body also having a vent forming passageway extending along one side of said chamber and terminating opposite said discharge outlet, and a rotatable and axially moveable valve operating stem connected to said valve member and extending through said valve body opposite said discharge outlet, said rotatable and axially moveable valve operating stem being adapted by its axial movement to open and close the discharge outlet of the valve body and by its rotary movement to open and close said vent forming passageway to the atmosphere when the discharge outlet of said valve body is open.
10. In a vented fluid controlling valve, the combination of a valve body having a fluid conduit and a vent forming passageway extending therethrough, an axially movable valve member for closing the fluid conduit through said valve body, a rotatable valve stem connected to said valve member having a portion adapted upon rotation of said stem to cooperate with said vent forming passageway to establish communication between said vent forming passageway and the atmosphere when said valve stem has been operated to move said valve member axially into its fluid conduit opening position, and means whereby said valve stem may be rotated when said valve member is in its open position to open and close said vent forming passageway without moving said valve member into its fluid conduit closing position.
11. In a vented fluid controlling valve, the combination of a valve body having a fluid conduit and a vent forming passageway extending therethrough, a valve member having both an axial and a rotary movement adapted to close and/or open the fluid conduit and the vent forming passageway in said valve body, and means for operating said valve member to impart an axial movement and open said fluid conduit and impart rotary movement to open and/or close said vent forming passageway.
12. In a vented fluid controlling valve, the combination of a valve body having a fluid con-

duit and a vent forming passageway extending therethrough, a valve member having both an axial and a rotary movement adapted to close and/or open the fluid conduit and the vent forming passageway in said valve body, means for operating said valve member to impart an axial movement and open said fluid conduit and im-

part rotary movement to open and/or close said vent forming passageway, and means cooperating with said last means for holding said valve member in its fluid conduit opening position while said last means is operated to open and/or close said vent forming passageway.

ALBERTO LOUIS MAGGENTI.
